US00D850978S

(12) **United States Design Patent** (10) **Patent No.:** **US D850,978 S**
Gao (45) **Date of Patent:** **** Jun. 11, 2019**

(54) **UNMANNED AERIAL VEHICLE**

(71) Applicant: **Shenzhen HighGreat Innovation Technology Development Co., Ltd., Shenzhen (CN)**

(72) Inventor: **Jianmin Gao, Shenzhen (CN)**

(73) Assignee: **SHENZHEN HIGHGREAT INNOVATION TECHNOLOGY DEVELOPMENT CO., LTD., Shenzhen (CN)**

(**) Term: **15 Years**

(21) Appl. No.: **29/617,622**

(22) Filed: **Sep. 14, 2017**

(51) LOC (11) Cl. **12-01**

(52) U.S. Cl.

USPC **D12/16.1**

(58) **Field of Classification Search**

USPC D12/16.1, 319-345; D21/436, 441, 442, D21/443, 444, 447-454

CPC B64C 2201/141; B64C 39/024; B64C 2201/127

(57) **CLAIM**

The ornamental design for the unmanned aerial vehicle, as shown and described.

DESCRIPTION

FIG. 1 is a front view of the unmanned aerial vehicle showing my new design;

FIG. 2 is a back view thereof;

FIG. 3 is a left view thereof;

FIG. 4 is a right view thereof;

FIG. 5 is a top view thereof;

FIG. 6 is a bottom view thereof;

FIG. 7 is a first perspective view thereof;

FIG. 8 is a second perspective view thereof; and,

FIG. 9 is a third perspective view thereof.

The broken lines in the drawings depict portions of the unmanned aerial vehicle that form no part of the claimed design.

1 Claim, 9 Drawing Sheets
